UNITED STATES PATENT OFFICE.

LAMARTINE C. TRENT, OF VANTRENT, CALIFORNIA.

CENTRIFUGAL FILTER.

No. 806,213.

Specification of Letters Patent.

Patented Dec. 5, 1905.

Application filed April 17, 1905. Serial No. 255,939.

To all whom it may concern:

Be it known that I, LAMARTINE C. TRENT, a citizen of the United States, residing at Vantrent, county of Placer, State of California, have invented certain new and useful Improvements in Centrifugal Filters; and I hereby declare the following to be a full, clear, and exact description of the same.

The present invention is designed for separating or expelling the water or liquid from the mass or body of material to be treated, such as slimes and peat and sugar, although the machine is equally as well adapted for the treatment of any material from which the water contained therein is to be removed or extracted, the object of the invention being to deliver the filtered material which is received in the form of a pulp in a solid and comparatively dry condition from the surface of a revolving screen onto the surface of which the material to be treated is delivered from any suitable source of supply.

To comprehend the invention, reference should be had to the accompanying drawings, wherein—

Figure 1 is a vertical sectional side view in elevation of the apparatus. Fig. 2 is a plan view of the screen onto which the material to be treated is delivered, and Fig. 3 is a plan view of the apparatus.

In the drawings the numeral 1 is used to indicate any suitable form of base which supports the circular platform 2 for receiving the filtered material delivered from the revolving screen. This platform is preferably cone-shaped, although it is apparent that such is an immaterial feature. Through the base 1 extends a vertical shaft 3, which works in the bearings 4 4'. To the lower projecting end 40 of this shaft is secured the bevel-gear 5, which gear meshes with a pinion 5', secured to the inner end of the longitudinally-arranged drive-shaft 6, said shaft being driven by means of a suitable pulley-belt (not shown) working over the pulley-wheel 6', attached to the outer end portion of the said shaft. The foregoing simply constitutes one form of means for imparting rotary motion to the vertical shaft 3, which, however, may be driven by any other suitable form of driving means.

To the vertical shaft 3 is fastened a collar 7, which is held such a distance above the base

1 as to permit of rotatable sleeve 7' being fitted onto the said shaft intermediate the collar 7 and the upper end of the base 1, Fig. 1 55 of the drawings. The upper face of the collar 7 is cut at an incline and on the same works the revolving circular screen-frame 8, which is held in place on the said collar by means of the vertical shaft 3, which shaft extends 60 loosely through an inclined or elliptical shaft-opening 8', formed through the hub 9 of the screen-frame. By means of this connection between the screen-frame and the vertical shaft 3 the said frame is free to rotate in an 65 inclined vertical plane on its own axis. The open sections 10 of the screen-frame are closed or covered by means of any suitable straining material 11, such as canvas or fine-mesh screen-wire or a combination of canvas and a 70 metallic reticulated material.

As the screen-frame, which shall hereinafter be termed a "screen," is supported on the inclined upper surface of the collar 7, which in turn is bolted or otherwise secured to the vertical shaft 3, it is obvious that as the said shaft 75 3 rotates horizontally on its own axis the screen will be revolved horizontally with the rotary motion of the said vertical shaft, the drive mechanism for which is so arranged as to impart a 80 rotation to said shaft of approximately four hundred revolutions per minute. The rotative speed of the said shaft is dependent greatly on the nature of the material to be treated, for certain materials may require that the shaft 85 be driven at a higher speed than four hundred revolutions per minute.

In order that the inclined screen may have rotation in a vertical plane on its own axis independent of the horizontal movement imparted thereto by the vertical shaft 3, there is secured to the under face of the screen's hub 9 a cog-ring 12. This ring meshes with the pinion 12', formed on the upper end of the sleeve 7'. The sleeve 7', which fits loose 90 on the shaft 3, has rotation imparted thereto from the drive-shaft 13, the gear 14 on the inner end thereof meshing with the gear 14' on the lower end of the said sleeve 7'. The rotary motion of the sleeve 7' is thus transmitted to impart vertical rotation to the inclined screen, the speed at which the screen is rotated being about one hundred revolutions per minute. However, this speed may be in-

creased or decreased; depending on the nature of the material to be worked. It will thus be observed that the screen has a horizontal rotation or movement imparted thereto by the rotary motion of the vertical shaft and that it also has a vertical rotation on its own axis independent of the rotation of the vertical shaft.

The angle of inclination at which the screen stands is dependent on the inclination given to the upper surface of the supporting-collar 7, which should be arranged as practical working may dictate. However, the inclination represented by the drawings is deemed the most suitable for the screen.

The upper end portion of the vertical shaft is made hollow for a given distance to provide a receiving-chamber 15, into which the pulp or semiliquid material to be treated is delivered. From the chamber 15 extends the chute or outlet-spout 15', through which the material discharges onto the upper surface of the inclined screen or filter disk.

To wash the face of the screen or filter disk for lubricating the surface thereof or to add moisture to the material being treated, a water-supply pipe 16 extends into the receiving-chamber and communicates with an outlet-passage 16'.

To an outwardly-extending flange 17, projecting from the collar 7', there is bolted a hopper 17'. This hopper is arranged above the horizontal center line of the screen and at the back thereof, the purpose being to receive the liquid constituents forced through the surface of the screen. This hopper communicates with a launder 18, into which is discharged the water separated from the material treated on the surface of the revolving screen and from which it is led to any suitable place of deposit.

In operation the vertical shaft is driven at a high velocity, similar to any ordinary centrifugal machine. The material to be treated is introduced into the receiving-chamber 15 and from thence is discharged from spout 15' onto the upper screen-surface portion of the inclined circular screen, which is being revolved horizontally with the vertical shaft, the screen at the same time being independently revolved in a vertical plane on its own axis, which constantly subjects a changing portion of the screen to the centrifugal influence. The liquid constituents of the material under treatment or discharged onto the upper surface of the screen will by centrifugal action due to the high speed at which the screen is revolved horizontally be forced through the meshes of the screen's surface always above the horizontal line and into the hopper or receiver 17'. Owing to the inclination of the orbit of the revolving screen, the material remaining thereon after having been carried

below the horizontal center line will be thrown by centrifugal action due to the high speed at which the screen is revolved vertically off of the screen onto the receiving table or platform 2, from whence the material may flow by gravity or be removed therefrom in any suitable manner. The weight of the moving parts of the machine is carried by the ball-bearing 19. The centrifugal strains due to the horizontal rotation thus act to force the liquid through the mesh of the screen's surface at the upper portion thereof, while the centrifugal strains due to the vertical rotation of the screen act to discharge the screened material from the lower half of the revolving screen onto the receiving table or platform.

Having thus described the invention, what is claimed as new, and desired to be protected by Letters Patent, is—

1. A filter for removing or separating the liquid from material to be treated, the same consisting of a screen arranged at an incline to the horizontal, of means for revolving the same in a horizontal plane at a high speed; of mechanism for simultaneously rotating the same in a plane at right angles to its own axis, and means for feeding the material to be treated onto the upper portion of the screen's surface during its rotary movement.

2. A filter for removing or separating the liquid from material to be treated, the same comprising a vertical shaft, of means for rotating the same about a vertical axis at a high speed, a screen fitted on said shaft at an angle to the horizontal, connection for moving said screen with the horizontal rotation of the vertical shaft, and means for independently rotating the screen in a plane at right angles to its own axis during the horizontal rotation of the vertical shaft.

3. A filter for the removing or separating of liquid from material to be treated, the same comprising a screen arranged at an angle to the horizontal, of means for revolving the same in a horizontal plane and simultaneously rotating the same in a plane at right angles to its own axis.

4. A filter for the removing or separating of liquid from material to be treated, the same comprising a screen set at an angle to the horizontal, of means for rotating the screen about a vertical axis, of independent means for simultaneously rotating the screen in a plane at right angles to its own axis, and a platform for receiving the material discharged from the rotating screen.

5. A filter for removing or separating liquid from material to be treated, the same comprising a screen arranged at an angle to the horizontal, of means for rotating the same in a horizontal plane and simultaneously imparting thereto rotation in a plane at right angles

to its own axis, means for delivering the material to be treated to the upper surface of the screen during its rotation, a device arranged at the back of the screen to receive the separated liquid, and a receiving-table below the screen onto which the material discharged therefrom is delivered.

In testimony whereof I have hereunto set my hand this 28th day of March, 1905.
